UNITED STATES PATENT OFFICE.

ALLAN P. LINDBLAD, OF EVERETT, MASSACHUSETTS.

DESIGN FOR A NAPKIN HOLDER.

Application filed June 2, 1925. Serial No. 13,639. Term of patent 14 years.

To all whom it may concern:

Be it known that I, ALLAN P. LINDBLAD, a citizen of the United States, residing at Everett, in the county of Middlesex and State of Massachusetts, have invented a new, original, and ornamental Design for Napkin Holder, of which the following is a specification, reference being had to the accompanying drawing, forming a part thereof.

I claim:

The ornamental design for a napkin holder, as shown.

In testimony whereof I have affixed my signature.

ALLAN P. LINDBLAD.
